(Cl. D80—8)

To all whom it may concern:

Be it known that I, Osgood Porter, a citizen of the United States and a resident of Santa Monica, in the county of Los Angeles and State of California, have invented a new, original, and ornamental Design for a Garment Hanger, of which the following is a specification, reference being had to the accompanying drawings, forming a part thereof.

Figure 3 is a bottom plan view;

Figure 4 is an end elevational view thereof; and

Figure 5 is a sectional view taken along line 5—5 of Figure 1.

The characteristic feature of my design for garment hanger resides in the specific configuration of the upper center portion thereof, having the downwardly facing U-shaped framework and the plate member arranged partially within and

extending downwardly below said framework, as shown, especially in Figure 1 of the drawing.

I claim:

The ornamental design for a garment hanger, substantially as shown and described.
